United States Patent Office

Des. 189,664
Patented Jan. 31, 1961

189,664

HIGH CHAIR

James F. Fulton, Center Line, Mich., assignor, by mesne assignments, to Trimble Products, Inc., Southern Pines, N.C., a corporation of North Carolina

Filed May 21, 1959, Ser. No. 56,010

Term of patent 14 years

(Cl. D15—1)

FIG. 1.

Des. 189,664

PAGE 2

FIG. 2.

Des. 189,664

PAGE 3

FIG. 3.

FIG. 4.

FIG. 5.

Fig. 1 is a front elevation of a high chair embodying my new design;

Fig. 2 is a side elevation of this high chair;

Fig. 3 is a rear elevational view, a dotted line indication of the retaining strap being shown therein for illustrative purposes only;

Fig. 4 is a top plan view of this high chair; and

Fig. 5 is a section on line 5—5 of Fig. 2 looking in the direction of the arrows, and constituting a fragmentary bottom plan view of the high chair.

I claim:

The ornamental design for a high chair, substantially as shown and described.
